US0D1065137S

(12) **United States Design Patent** (10) **Patent No.:** **US D1,065,137 S**
(45) **Date of Patent:** **** Mar. 4, 2025**

(54) **PORTABLE MEDIA PLAYBACK DEVICE**

(71) Applicant: **Sonos, Inc.**, Santa Barbara, CA (US)

(72) Inventors: **Daehoo Kim**, Oxnard, CA (US); **Aki Laine**, Santa Barbara, CA (US); **Edward Mitchell**, Thousand Oaks, CA (US)

(73) Assignee: **SONOS, INC.**, Goleta, CA (US)

(**) Term: **15 Years**

(21) Appl. No.: **29/879,581**

(22) Filed: **Jul. 10, 2023**

Related U.S. Application Data

(63) Continuation of application No. 29/748,673, filed on Aug. 31, 2020, now Pat. No. Des. 995,479.

(57) **CLAIM**

The ornamental design for a portable media playback device as shown and described.

DESCRIPTION

FIG. 1 is a rear elevation view of a portable media playback device, according to our new design;

FIG. 2 is a front elevation view thereof;

FIG. 3 is top plan view thereof;

FIG. 4 is a bottom plan view thereof;

FIG. 5 is a first side view thereof;

FIG. 6 is a second side view thereof;

FIG. 7 is a first perspective view thereof; and,

FIG. 8 is a second perspective view thereof.

The dashed broken lines in the figures illustrate the portions of the portable media playback device that form no part of the claimed design.

1 Claim, 6 Drawing Sheets
